L. E. BRADY.
DEVICE FOR PLAYING GAMES.
APPLICATION FILED MAR. 11, 1920.

Patented Feb. 8, 1921.

Inventor
L. E. Brady
By Franklin D. Slagle

Attorney.

UNITED STATES PATENT OFFICE.

LEVI ELI BRADY, OF ST. LOUIS, MISSOURI.

DEVICE FOR PLAYING GAMES.

1,367,585.

Specification of Letters Patent. Patented Feb. 8, 1921.

Application filed March 11, 1920. Serial No. 364,960.

To all whom it may concern:

Be it known that I, LEVI ELI BRADY, a citizen of the United States, residing in the city of St. Louis and State of Missouri, have 5 invented certain new and useful Improvements in Devices for Playing Games; and I do hereby declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 The object of this invention is to provide a novel toy, which may be used as an adjunct to different games.

With this object in view, the invention resides, briefly stated, in a flexible, somewhat resilient, member adapted to be placed upon a suitable support and hit upon one 20 end thereof by the finger of the operator or by a suitable tool to cause the same to bounce through the air. The accompanying drawing 25 clearly discloses an exemplary form of the device. Briefly described:

Figure 1 is a perspective view of the toy in the act of moving through the air after being struck to cause the same to rise from 30 the ground or other support.

Fig. 2 is a view in side elevation of the toy,

Fig. 3 is a bottom plan view, and

Fig. 4 is a top plan view.

35 Referring now in detail to the drawing:

The toy is preferably formed as a strip 1 of suitable flexible and resilient material, such as thin steel. The strip is desirably weighted toward one end thereof, as shown 40 at 2, and toward the other end thereof, is advantageously bent, as shown at 3 to provide a transversely V-shaped portion. From the bent portion 3 to the unweighted end of the strip, the strip is inclined upward, as 45 shown at 4.

By preference, the upwardly inclined portion 4 of the toy is provided with radial ribs 5. Also, if desired, the portion 4 may be slightly concaved to conform to the curvature of the end of the operator's finger.

50 The weight 2, at one end of the toy, is disposed beneath the strip 1, as shown.

In operation, the toy is disposed on a suitable support, such as the ground, with the weight 2 and the bottom of the V-shaped portion 3 resting upon the ground, and the portion 4 at an angle to the ground. The portion 4 may be called the trigger, and may be struck a sharp or quick blow by the operator's finger, or by a stick 6, or other 55 operating means, whereupon the toy will rise from the ground and fly through the air a short distance. The distance the toy will fly through the air will depend, of course, upon the dimensions of the toy and upon the 60 factors of resilience, etc., and upon the degree of force which is exerted upon the trigger 4.

I have found by experiment that the best results are obtained by inclining the trigger 4 at an angle of 45° to the support upon which the toy rests, and, in fact, this degree of angularity is most important in order to obtain the proper operation of the device. With a toy having an overall length of 2 $\frac{1}{4}$ " 75 and a width of approximately $\frac{1}{2}$ ", and constructed of thin steel, the toy will fly through the air from two or three inches to four or five feet, according to how hard the operator strikes the trigger 4.

80 What I claim to be new is:

1. An aerial toy, comprising a resilient strip, provided toward one end with a transversely bent V-shaped portion and with an upwardly inclined portion constituting a 85 trigger adapted to be struck by the operator to cause the toy to rise into the air.

2. An aerial toy, comprising a resilient strip weighted at one end and provided toward the other end with a transversely bent 90 V-shaped portion and with an upwardly inclined portion adapted to be struck by the operator to cause the toy to ascend into the air.

3. An aerial toy comprising a resilient 95 strip, provided toward one end with an upwardly inclined portion slightly concaved to conform to the curvature of the end of the operator's finger, said portion constituting a trigger to be struck by the operator 100 to cause the toy to ascend.

In testimony whereof I hereunto affix my signature.

LEVI ELI BRADY.
